ATTYS.

UNITED STATES PATENT OFFICE.

GEORGE E. BRUNER, OF LOS ANGELES, CALIFORNIA.

GAME.

1,344,983.

Specification of Letters Patent. Patented June 29, 1920.

Application filed May 31, 1918. Serial No. 237,592.

To all whom it may concern:

Be it known that I, GEORGE E. BRUNER, a citizen of the United States, residing at Los Angeles, in the county of Los Angeles and State of California, have invented new and useful Improvements in Games, of which the following is a specification.

My invention relates to games and consists in the novel features herein shown, described and claimed.

Figure 1 is a plan illustrating a game embodying principles of my invention.

Fig. 2 is a perspective of a "guard".

Fig. 3 is a perspective of a "man".

15 In Fig. 1 I have shown two game boards 1 and 2 placed to meet on the line 3 for playing a three-handed or a four-handed game. The boards 1 and 2 are substantially alike and either board may be used independently 20 of the other for playing a two-handed game. Each board is substantially a right-angle triangle.

In laying off the board 1, the fields 4 and 5 meet on the line 6, said line 6 dividing the 25 board 1 into two equal right-angle triangles. A row of spots 7, 8, 9 and 10 is formed on the line 6, said spots being preferably square and joining corner to corner, and these spots are distinguished by five-pointed stars and 30 the row is designated the "guard row". The game is called "trisq", and the "trisq" 11 is the "home ground" and is bounded by the lines 12 and 13 extending from the inner 35 end of the guard row parallel with the lines 14 and 15 and extending to the line 3 and forming a small right-angle triangle. The remaining space of the field 4 consists of a row of spots 16 and 17 in line with the spot 10 and joining the line 13, the spots 18, 19 40 and 20 in line with the spot 9 and joining the spots 16 and 17 cornerwise, the spots 21, 22, 23 and 24 in line with the spot 8 and joining the spots 18, 19 and 20 cornerwise, the spots 25, 26, 27, 28 and 29 in line with 45 the spot 7 and joining the spots 21, 22, 23 and 24 cornerwise, and the spots 30, 31, 32, 33, 34 and 35 outside of the line of the spot 7 and joining the spots 25, 26, 27, 28 and 29 cornerwise, thus making twenty playing 50 spots, 16—35 inclusive, for the player using the field 4.

In a like manner twenty spots, 36, 37, 38, 39, 40, 41, 42, 43, 44, 45, 46, 47, 48, 49, 50, 51, 52, 53, 54 and 55 are laid off in the field 5 to 55 be used as playing spots for the player using that field.

In a like manner the fields 56 and 57 of the board 2 are laid off with spots 58, 59, 60, 61, 62, 63, 64, 65, 66, 67, 68, 69, 70, 71, 72, 73, 74, 75, 76 and 77, inclusive, and 78, 79, 80, 60 81, 82, 83, 84, 85, 86, 87, 88, 89, 90, 91, 92, 93, 94, 95, 96 and 97, inclusive, and the "trisq" 98 and the "guard row" spots 99, 100, 101 and 102.

Each board 1 and 2 has half spots along 65 the line 3 to form the "guard row" spots 103, 104, 105, 106, 107, 108, 109 and 110. When the boards are used separately these "guard row" spots 103—110 are of no significance.

In playing a two-handed game on the 70 board 1, the "guards" 111 are placed on the spots 18, 21 and 25, and 20, 24 and 29, and "men" 112 are placed on the spots 19, 22, 23, 26, 27 and 28. The "guards" 111 and "men" 112 constitute the force of the player using 75 the field 4 and this force will be designated by a distinctive color, such as black, and the "guards" 111 will be distinguished from the "men" 112 by a distinctive form. As shown in Figs. 2 and 3 the "guards" 111 have convex tops 113 and the "men" 112 have concave tops 114. In a like manner the player using the field 5 will have six "guards" and six "men" of a color such as white to distinguish from the black "men", the "guards" being 80 placed upon the spots 40, 44, 49, 38, 41 and 45, and the "men" upon the spots 39, 42, 43, 46, 47 and 48.

If a three-handed game is to be played the third player will use either the field 56 90 or 57 and will use a set of "guards" and "men" of a third distinguishing color such as red, and if a four-handed game is to be played the fourth player will have a fourth set of "guards" and "men" of a fourth distinguishing color such as purple.

When a three-handed game is to be played, the best player should occupy the field between the other two players and then he has a "guard row" on each side of his 100 field while the other two players have a "guard row" only on one side of their fields.

When a four-handed game is to be played the four "guard rows" come into use and the game should be played as partners, two 105 on a side.

If desired, two people can play a four-handed game.

In laying out the boards, the background 115 is preferably of a light color, such as 110 white or yellow, and the playing spots are preferably dark, such as black or blue or

may be of any color which will contrast with the background. The "guard rows" may be distinguished from the other playing spots by stars, or in any other suitable way 5 as by a contrasting color. Preferably the "trisq" or "home ground" is of a color that will contrast with all the other colors, such as green.

The sets of "guards" and "men" may be 10 of any of the button forms, the only requirement being that the "guards" may be readily distinguished from the "men" of the same set, and that the sets may be readily distinguished from each other.

15 With the "guards" and "men" arranged as shown on the fields 4 and 5, a two-handed game is ready to start. The "guards" and "men" are moved diagonally from one spot to the next and jumped diagonally. The 20 game is to jump the "guards" and "men" into the "home ground" or "trisq" and the player having the most "guards" or "men" in the "home ground" or "trisq" when all of one set of "guards" and "men" are off the 25 board wins the game. When one player jumps a "guard" or "man" of the opposing player the jumped "guard" or "man" is not removed from the board. The "guards" and "men" are eliminated from the board by 30 jumping off the board. Every possible jump is compulsory except that a "guard" in a "guard row" need not jump unless he chooses except when an opposing "guard" is on the "guard row" in position to be jumped, 35 and a "guard" on the "guard row" cannot be jumped except by an opponent's "guard" on the "guard row." Any jump over the spots 30, 31, 32, 33, 34, 35, 50, 51, 52, 53, 54 and 55 will carry the jumper off the board 40 and eliminate the jumper. Also a jump from 34 over 29, 28 over 24, 23 over 20, or 54 over 49, 48 over 44, 43 over 40 will carry the jumper off the board and eliminate the jumper. Any jump over 17, 16, 36, or 37 45 will carry the jumper into "trisq." Also a jump from 9 over 10 will carry the jumper into "trisq." Of course, an equal number in "trisq" at the end of the game is a draw. No player may jump back to the spot from 50 which he started at one move but must stop on the spot from which he would jump to reach the starting spot.

A four-handed game may be played by four people or two people in the same way 55 and various other games and various other rules may be worked out and played.

The board faces may be painted or printed on cardboard, cloth, or the like, and may be made separately, or the two board faces

may be made integral. Of course, the 60 board faces may be printed or painted directly upon the boards.

The "guards" and "men" are generally termed "men."

Various changes may be made without departing from the spirit of my invention as 65 claimed.

I claim:

1. In a game, two triangular fields having playing spots in rows at right angles to each other; there being "guard row" playing spots on the line between the fields, playing spots on each field, said playing spots being arranged in diagonal relation to the playing spots immediately adjacent thereto, and a "home ground" in the corner between the two sets of playing spots at the inner end of the "guard row." 70

2. A game comprising a right-angled-triangular game board face divided into two 80 equal right-angled-triangular fields; there being four "guard row" playing spots on the line between the fields and twenty playing spots in each field, said playing spots being arranged in diagonal relation to the playing spots immediately adjacent thereto, and a "home ground" at the inner end of the "guard row"; in combination with two 85 distinguishable sets of "men."

3. A game comprising a right-angled-triangular game board face divided into two 90 equal right-angled-triangular fields; there being four "guard row" playing spots on the line between the fields and twenty playing spots in each field, said playing spots being arranged in diagonal relation to the playing spots immediately adjacent thereto, and a "home ground" at the inner end of the "guard row"; in combination with two 95 distinguishable sets of "guards and men," each set comprising six "guards" and six "men," the "guards" and "men" being distinguishable from each other. 100

4. A game comprising a square game board face having a square "home ground" 105 in the center, four fields separated by lines extending from the corners of the "home ground" to the corners of the game board face, four "guard row" playing spots on each line, and twenty playing spots on each 110 field; said playing spots being arranged in diagonal relation to the playing spots immediately adjacent thereto, in combination with four distinguishable sets, each set comprising six "guards" and six "men." 115

In testimony whereof I have signed my name to this specification.

GEORGE E. BRUNER.
